UNITED STATES PATENT OFFICE.

FREDERIC E. BERTRAND, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-FILLING MACHINE.

1,299,665.

Specification of Letters Patent.

Patented Apr. 8, 1919.

Application filed May 21, 1915. Serial No. 29,594.

To all whom it may concern:

Be it known that I, FREDERIC E. BERTRAND, a citizen of the United States, residing at Lynn, in the county of Essex and State of

5 Massachusetts, have invented certain Improvements in Shoe-Filling Machines, of which the following description, in connection with the accompanying drawings, is a specification, like reference characters on the 10 drawings indicating like parts in the several figures.

This invention relates to machines for filling shoes and is herein illustrated in connection with a machine for applying to a shoe 15 a heated filling material.

The filling material commonly used consists of a comminuted solid such as cork held together by a sticky binder, the whole mass when cold being solid but taking on when 20 properly heated and mixed a viscous character to the extent that it may be forced through a comparatively small opening and pressed into a cavity of any shape to which it is applied. It is customary to fill the cavity 25 in the bottom of a shoe, bounded by the inseam from the toe up to or including the shank, with such a material preparatory to laying and attaching the outer sole. Hitherto, because of the sluggish nature of the 30 filling material, it has been difficult to force it properly in a continuous stream from the receptacle into the cavity.

One feature of the present invention comprises, in a machine of the class described 35 having a receptacle for filling material and an outlet through which the material is forced to the bottom of the shoe, a pressure chamber in which a comparatively small amount or charge of the material is subjected to considerable pressure during the 40 time that the outlet is open. By thus segregating a small portion of the material and concentrating the pressure upon it a much more satisfactory delivery may be made.

45 This and other features of the invention including certain details of construction and combinations of parts will be described in connection with an illustrative machine and pointed out in the appended claims.

50 Referring to the accompanying drawings,—

Figure 1 is a front view, partly in section, of a machine in which the present invention is embodied;

Fig. 2 is a section on the line 2—2 of 55 Fig. 1;

Fig. 3 is a plan view with certain parts in section and others broken away.

Before going into a detail description of the machine its general mode of operation 60 will be outlined. The filling material in the form of bricks or chunks is placed in a preliminary heating chamber where it is somewhat softened by heat and broken up or comminuted by revolving shredders. From 65 this chamber it falls into the main receptacle where it is further softened or melted and thoroughly mixed and stirred so as to maintain it in proper condition to be delivered to a shoe. Communicating with the lower 70 part of the main receptacle is a small compartment which is intermittently separated from the main compartment by a valve which closes the communication. The material in this compartment is compressed by a plunger 75 prior to the opening of a valve which permits the compressed material to flow upon a shoe presented in proper position to the machine.

The preliminary heating chamber 1, the 80 melting chamber 3, and the associated parts are mounted on a pedestal 5 so as to permit convenient presentation of a shoe to the machine. A shaft 7, rotatably mounted in the lower part of the heating chamber 1, is 85 connected by gears 9 with shafts 11 upon which are mounted shredders 10. A steam jacket 13 surrounds the lower part of the chamber 1 and serves to soften the filling material while said material is being broken 90 up by the action of the shredders. The main receptacle 3 into which the partially softened and broken material drops, has formed in its sides and bottom a second steam jacket 95 15 and is provided with a mixer or stirrer 17 the contour of the outside edge of the arms of which, as shown in Fig. 1, corresponds to the contour of the lower part of the receptacle. The stirrer 17 is fast to short shafts 19; and a chain 21 connects a sprocket 100 wheel 23 loose on the end of one of said shafts with a sprocket wheel 25 on the end of the shaft 7. The other short shaft 19 is connected by a friction drive with a pulley 26 to which power may be applied by means 105 of a belt, the purpose of the friction drive being to prevent breakage of parts which might occur under certain circumstances

when the stirrer is started. A clutch member 27 which is keyed to but slideable on the right hand shaft 19 may be moved when desired by a handle 29 to connect the sprocket 5 wheel 23 with said shaft. With this construction the stirrer 17 may be rotated continuously and the shredding mechanism, operated by the shaft 7, may be thrown into or out of action as desired.

10 The bottom of the receptacle 3 opens into an inclined pressure chamber 31 rectangular in cross-section in which a plunger 33 is slideable; and above the plunger a valve 35 is slideable in ways in the walls of the pressure chamber. Communicating with the lower end of the pressure chamber 31 is an oscillatory delivery valve 37 held in a cylindrical valve casing 39 having a long narrow opening 41 in its under side which is normally closed by two gate valves 43. The oscillatory valve 37 has a large receiving opening 45 which is always in communication with the pressure chamber 31, and a smaller delivery opening 47 which is normally out of register with the opening 41 in the casing 39 but is moved into register with said opening whenever a shoe is to be filled.

15 The various movements of the slide valve 35, the plunger 33 and the oscillatory valve 37 take place when the operator depresses a treadle, not shown. The slide valve 35 has a boss at its upper end to which one end of a link 49 is pivoted, the other end of the link being pivoted to an arm 51 the hub of which is loose upon a shaft 53, said hub having extending outwardly from it a second arm 55 which has a pin and slot connection with a rod 57 so that when said rod is lowered and raised the valve 35 is closed and opened. The plunger 33 is connected by links 61 with arms 59 the hubs of which are fast to the shaft 53. The hub of an arm 63 is also fast to said shaft, the outer end 20 of said arm having a pin-and-slot connection with an operating rod 65. The oscillatory valve 37 is provided with depending tails to which are pivoted one end of links 67 the other end of said links being pivoted to arms 68 fast to a rock-shaft 68 to which is also fast an arm 69 having a pin-and-slot connection with an operating rod 71. The rods 57, 65 and 71 may be reciprocated in any suitable manner as, for example, by rolls 55 which run in properly shaped cam tracks, the whole mechanism being controlled by any suitable form of one-revolution clutch. Since mechanism of this sort is well known no specific mechanism has been shown. It 30 will be understood, however, that the machine comes to rest with the parts in the position shown and that when the operator depresses the treadle to throw in the one-revolution clutch the rods 57, 65 and 71 are reciprocated in properly timed relation. It

will be noted that the rod 65 is held down by a rod 73 through a spring 75, the purpose of the spring being to apply a yielding pressure to the plunger 33. When the one-revolution clutch referred to above has been thrown in, the valve 35 is first moved to shut off the pressure chamber 31 from the main receptacle 3, the plunger 33 is then moved downwardly to apply pressure to the filling material in the chamber 31, and then 75 the valve 37 is oscillated to bring the opening 47 into register with the opening 41 in the valve casing 39. It will therefore be evident that if the gate valves 41 are now open a ribbon-like mass of filling material 80 will be forced out, the width of said ribbon-like mass depending upon the distance apart of the adjacent ends of the gate valves 43.

These gate valves are normally held in position by a spring and are arranged to be 85 opened by the presentation of a shoe in position to be filled, the extent to which they are opened varying in accordance with the width of the shoe in the manner which will now be described. The valve casing 39 is 90 held fast in a cylindrical socket in a depending portion 30 of the receptacle 3, said portion having a curved extension in which is formed a slideway for the valves 43 which are similarly curved. Each valve 43 is provided with a socket to receive a pin 77 carried by an arm 79; and pivoted to the arms at 81 are other arms 83 upon the ends of which are rotatably mounted contacting members 85 in the form of rollers. Each arm 83 has a depending tail adapted to be engaged by a set screw 87 by which the position of the roller 85 may be adjusted. The arms 79 are integral with hubs 89 each of which is provided with a second arm 91 having formed on its end a segmental gear 93. These gears intermesh so that when one of the rollers 85 is moved in a given direction the other roller will be moved equally in an opposite direction. A spring 97 connects the two arms 79 thereby holding the rollers 85 in the position shown with the gate valves in closed position. In order to permit the rolls 85 to be separated if desired just prior to the presentation of a shoe to the machine 115 a chain 99 connected with a suitable treadle (not shown) passes over a roller 101 and is fastened to one of the arms 91.

In the operation of the machine steam or any suitable heating fluid is admitted to the jackets 13, 15, power is applied to the pulley 26 and the clutch 27 thrown in. The preliminary heating chamber 1 is then partially filled with the cold filling material. In this chamber the material is somewhat softened by the heat and broken up by the shredders 10 on the shafts 7 and 11. The partially heated and broken filling material drops into the main receptacle 3 where it is further heated and in addition acted upon by 125 130

the stirrer 17 to work it up into the proper consistency for being applied to a shoe. When a sufficient amount of filling material has accumulated in the receptacle 3 the 5 operator presents a shoe between the rolls 85, throws in the one-revolution clutch, which has been referred to above, and moves the shoe along beneath the outlet 41. As the clutch is thrown in the material in the 10 pressure chamber 31 is subjected to pressure, and the delivery opening 47 in the valve 37 brought into register with the opening 41. The cams which operate these elements are so arranged that the valve 35 remains closed, 15 the opening 47 in register with the opening 41 and the plunger in position to apply pressure to the material for a time sufficient to permit the shoe to be filled. As the rolls 85, which run in the rand crease of the shoe, 20 are forced apart more or less by the movement imparted to the shoe by the operator, a ribbon of filling material is delivered upon the bottom of the shoe. In practice it is possible either to push the shoe toe foremost 25 until the rollers 85 reach the shank of the shoe and then to release the shoe by the chain 99 or to open the rollers slightly by means of the chain 99 and start the filling operation at or near the shank of the shoe. In the second 30 case the operator pulls the shoe toward him instead of pushing it away from him as in the first case. As the filled portion of the shoe passes the rollers 85 the operator may tilt it slightly to cause it to drag over the 35 lower surface of the valve casing 39 so as to smooth the filling material and press it into place.

The purpose of the curve of the extensions 30 and the valves 43 is to provide for 40 the usual transverse curvature of the bottom of the shoe and to cause the filling material to be slightly crowned.

Although the invention has been set forth 45 in connection with a particular machine, it should be understood that the invention is not limited in the scope of its application to the particular machine shown and described.

Having thus described my invention, I 50 claim as new and desire to secure by Letters Patent of the United States:

1. A shoe filling machine, having in combination, a receptacle for filling material, a pressure chamber having an inlet from said receptacle and an outlet, a valve controlling said inlet, a second valve controlling said outlet, means for closing the inlet valve, means for applying pressure to the material in said chamber while said inlet valve is closed, and means operated by presentation 55 of a shoe in operative relation to said outlet for opening said outlet valve.

2. A shoe filling machine, having in combination, a receptacle for filling material, a pressure chamber having an inlet from said

receptacle and an outlet, a valve controlling 65 said inlet, a second valve controlling said outlet, means for closing the inlet valve, means for applying pressure yieldingly to the material in said chamber while said inlet valve is closed, and means operated by 70 presentation of a shoe in operative relation to said outlet for opening said outlet valve.

3. A shoe filling machine, having in combination, a receptacle for filling material, a pressure chamber having a normally open 75 inlet from said receptacle and a normally closed outlet, power operated means for closing said inlet and compressing the material in said chamber, and means operated upon presentation of a shoe in position to be filled 80 for opening said outlet.

4. A shoe filling machine, having in combination, a receptacle for filling material, a pressure chamber having a normally open inlet from said receptacle and a normally 85 closed elongated outlet, a valve for controlling said inlet, a pair of gate valves for controlling said outlet, power operated means for closing said inlet valve and compressing 90 the material in the pressure chamber, and means operated by presentation of a shoe in position to be filled for opening said gate valves.

5. A shoe filling machine, having in combination, a receptacle for filling material, a pressure chamber in communication with said receptacle, a valve casing opening at one point into said chamber and being provided at another point with an outlet, a valve in said casing having communication 95 at all times with said chamber to receive filling material therefrom, said valve being provided with a delivery opening, means for applying pressure to the material in said pressure chamber, means for moving said valve to cause its delivery opening to register with said outlet, and means operated 100 upon presentation of a shoe for opening said outlet.

6. A machine of the class described having, in combination, a receptacle for filling material, a pressure chamber in communication with said receptacle, a valve casing opening at one point into said chamber and being provided at another point with an outlet, a valve in said casing having communication 110 at all times with said chamber to receive filling material therefrom, said valve being provided with a delivery opening, means for applying pressure to the material in said pressure chamber, means for moving said valve to cause its delivery opening to register with said outlet, and means for 115 opening and closing said outlet.

7. A machine of the class described having, in combination, a receptacle for filling material, there being an outlet from said receptacle, the portion of the machine through 120

which said outlet opens having a face against which the bottom of the shoe is pressed during the filling operation of the curvature desired to be imparted to the bottom of the filled shoe, and means for forcing filling material through said outlet.

8. A machine of the class described having, in combination, a receptacle for filling material, there being an outlet from said receptacle, the portion of the machine through which said outlet opens having a face against which the bottom of the shoe is pressed during the filling operation of the curvature desired to be imparted to the bottom of the filled shoe, and means constructed and arranged to be operated when the shoe is moved along in contact with said face for causing filling material to be delivered to the bottom of said shoe.
- 10 9. A machine of the class described having, in combination, a chamber in which the filling material is heated and disintegrated, a receptacle in which the filling material is melted and stirred, rotary shafts mounted respectively in the walls of said chambers, means for applying power to one shaft to rotate it, and means for connecting the other
- 15
- 20
- 25

shaft with the power shaft and for disconnecting it therefrom.

10. A shoe filling machine having, in combination, a receptacle for filling material, a pressure chamber having an inlet from said receptacle and an outlet, a normally open inlet valve, a normally closed outlet valve, means for closing the inlet valve and compressing the material in the chamber, and means operated upon presentation of a shoe in position to be filled for opening the outlet valve.

11. A shoe filling machine, having, in combination, a receptacle for filling material, a pressure chamber having an inlet from said receptacle and an outlet, a valve controlling said inlet, a second valve controlling said outlet, means for closing the inlet valve, yieldingly operated reciprocating means for applying pressure to the material in said chamber while said inlet valve is closed, and means for opening said outlet valve.

In testimony whereof I have signed my name to this specification.

FREDERIC E. BERTRAND.
